UNCOUPLING MECHANISM

Filed Aug. 2, 1926

UNITED STATES PATENT OFFICE

WILLIAM J. REGAN, OF WILKINSBURG, PENNSYLVANIA, ASSIGNOR TO THE MC CONWAY & TORLEY COMPANY, OF PITTSBURGH, PENNSYLVANIA, A CORPORATION OF PENNSYLVANIA

UNCOUPLING MECHANISM

Application filed August 2, 1926. Serial No. 126,821.

My invention relates to uncoupling mechanism for operating the locking device of a car coupler, and is particularly designed to overcome accidental release of the lock-to-the-lock of the coupler locking mechanism which is often induced by vibration of the outer arm of an uncoupling lever of the well known jointed type.

In an uncoupling mechanism of the jointed lever type, such as is illustrated in the drawings, the lever members are so nearly in equilibrium about their common pivotal point that a comparatively small force applied to the free end of the outer lever will sufficiently float or raise the inner end of the inner lever to actuate the lock-to-the-lock device and cause it to assume a position permitting the knuckle locking block of the coupler to be moved or jarred to lock-set position, thereby allowing the knuckle of the coupler to open accidentally. Because of the condition of the tracks, the condition and construction of the car bodies, trucks, etc., trains when operating at high speeds cause very rapid movements of all of the parts of such uncoupling levers are free to vibrate upward and downward, and these movements cause the outer arm of the uncoupling lever to develop considerable force which may result in a sufficient raising of the inner end of the lever mechanism to destroy the effectiveness of the lock-to-the-lock device of the car coupler. The present invention provides means for opposing an accidental rotation of the outer lever member from locked to unlocked position.

The principal feature of the invention, generally stated, consists in employing in combination, an uncoupling lever device comprising relatively movable rotatable lever members one of which extends inwardly from its center of rotation so as to engage and actuate the lock-to-the-lock device of a coupler locking mechanism and the other of which extends from its center of rotation outwardly toward the side of the car so as to be manually operable to effect an unlocking movement of the inwardly extending member, and means for resisting accidental movement of

the manually operable lever member from its locked toward an unlocked position.

A further feature of the invention consists in employing, in combination with an uncoupling mechanism of the lever type indicated, a plurality of members carried by the car in position to embrace and engage the outer lever member, one of the embracing members being shouldered and one being adapted to yield when the outer lever member is operated manually.

In the drawings illustrating the invention, the scope whereof is pointed out in the claims:

Figure 1 is a plan view of a portion of a freight car equipped with an uncoupling mechanism embodying the invention.

Figure 2 is an end elevational view of the construction shown in Figure 1.

Figure 3 is a detail sectional view on the line 3—3 Figure 1.

The car coupler 1 illustrated in the drawings is of the well known standard D form having a lock lifter 2 of the general type shown in the William Kelso Patent No. 1,294,343, granted February 11, 1919, which also performs the function of a lock-to-the-lock preventing the knuckle locking block from accidentally assuming unlocked position.

The uncoupling mechanism by which the lock of the car coupler is moved to unlocked position is of the familiar lever style comprising an inner lever member 3 and an outer lever member 4. These two members are mounted for independent rotation upon a common pivot pin or bolt 5 which projects from a bracket 6 secured to the car body. The inner end of the member 3 extends through the usual eye in the upper end of the lock lifter 2, while the inner end of the member 4 is formed with an offset portion 7 which extends under the lever member 3. By this means a downward movement of the outer end of the lever member 4 effects an upward movement of the inner end of the lever member 3, thereby first moving the lock lifter 2 from lock-to-the-lock position and thereafter effecting an unlocking movement of the coupler lock in the well known way.

The means for preventing the outer lever

member 4 from accidentally performing an unlocking movement may advantageously be secured to the end sill of the car and preferably consist of a rigid member 8 associated with a spring member 9. These two members may conveniently be of angular form, their upper portions being disposed in overlapped relation and being secured to the end sill 10 by rivets 11. The depending portions of the members 8 and 9 are spaced from each other to receive the outer lever member 4 between them. The member 9 is preferably made of thin spring steel so that it may be sprung readily when the uncoupling lever is operated either by hand or foot. Instead of forming the member 8 of spring steel it preferably is substantially rigid, being either cast or fashioned from a bar of relatively heavy cross section. At its lower end the member 8 is provided with a bent or offset portion 12 extending toward the spring member 9 so as to provide upper and lower inclined guiding faces 13 and 14 respectively, for cooperating with the outer end of the lever member 4. As will be readily understood, when this lever member is actuated to unlock the coupler its movement in contact with the inclined face 13 flexes the spring tongue so as to permit the lever 4 to fully perform a coupler unlocking movement. Similarly, when the lock of the coupler falls to locked position the incline 14 at the lower end of the rigid member 8 cooperates with the lever 4 so as to enable the latter to press the spring member 9 outwardly for a distance sufficient to permit said lever to re-assume its normal locked position as illustrated in Figure 3. It will be perceived that the means for preventing the lever from accidentally moving from locked toward unlocked position are simple, effective and entirely automatic in operation.

I claim:

1. In uncoupling mechanism for car couplers having a lock-to-the-lock for preventing the coupler lock from accidentally moving to unlocked position, the combination of an uncoupling lever comprising an inner lever member and an outer lever member, said lever members being relatively rotatable about a common pivotal point and said outer lever member being rotatable downwardly from normal position to effect an unlocking rotation of said inner lever member, and means embracing said outer lever member for yieldingly opposing rotation of said last-named member, said means including yieldingly separable parts and being provided with a plurality of inclined faces respectively adapted to cooperate with said outer lever member to effect relative spreading of said parts, one of said inclined faces being cooperable with said outer lever member during a downward unlocking rotation of the latter, and one of said inclined faces being co-

operable with said outer lever member during an upward rotation of the latter from unlocked toward normal position, and said embracing means acting under service conditions to prevent accidental downward movement of the outer lever member from normal position to a position effecting unlocking of the lock-to-the-lock. 70

2. In uncoupling mechanism for car couplers having a lock-to-the-lock for preventing the coupler lock from accidentally moving to unlocked position, the combination of an uncoupling lever comprising an inner lever member and an outer lever member, said members being relatively rotatable about a common pivotal point and said outer lever member being rotatable downwardly from normal position to effect an upward rotation of said inner lever member, and means embracing said outer lever member for yieldingly opposing downward rotation of the latter from normal position, said means comprising a plurality of members including a spring tongue and being provided with upper and lower inclined faces respectively adapted to cooperate with said outer lever member, said upper inclined face being cooperable with said outer lever member during downward rotation of the latter from normal position to flex said spring tongue, and said lower inclined face being cooperable with said outer lever member during upward rotation of the latter from unlocked toward normal position to flex said tongue, and said embracing means acting under service conditions to prevent accidental downward movement of the outer lever member from normal position to a position effecting unlocking of the lock-to-the-lock. 80

In testimony whereof I affix my signature. 90
